UNITED STATES PATENT OFFICE.

WARREN K. DODGE, OF MANHATTAN, KANSAS.

ELECTRIC SWITCH.

SPECIFICATION forming part of Letters Patent No. 752,531, dated February 16, 1904.

Application filed October 23, 1903. Serial No. 178,235. (No model.)

To all whom it may concern:

Be it known that I, WARREN K. DODGE, a citizen of the United States, and a resident of Manhattan, in the county of Riley and State 5 of Kansas, have made certain new and useful Improvements in Electric Switches, of which the following is a specification.

My invention is in the nature of an electric switch so constructed and arranged that two 10 or more lights or sets of lights or any combination of the same may be thrown into circuit and the circuits which are "on" are plainly indicated from the exterior of the case.

15 It consists in the novel construction and arrangement of the switch and in the combination with the same of an indicator which plainly shows what circuits are turned on even in the dark, as will be hereinafter fully 20 described with reference to the drawings, in which—

Figure 1 is a plan view of the exterior of the switch and case. Fig. 2 is a similar view, with the mask-plate removed and the switch- 25 stem in section. Fig. 3 is an interior plan view with the casing removed. Fig. 4 is a vertical central section taken on the line 4-4 of Fig. 3, and Fig. 5 shows a diagram of the circuits.

30 In the drawings, A represents the base of the switch, which is a circular disk of some non-conducting material, such as porcelain, hard rubber, or wood.

B is the outer casing, which is a circular 35 cup that extends over the top and down along the sides of the switch and fits closely to the edges of the base-plate of porcelain. This casing incloses the working parts of the switch proper.

40 The numeral 1 indicates a plate with which there connects a main-line wire M', and 4 and 4^a are the plates with which connect the branch lines M² M³, to either or both of which the current from main line M' may be directed.

45 The plate 1 has a spring-arm 1^a, which rests normally against a lug 2^a on a plate 2. This spring-arm 1^a is bent and extends through a slot in the side of the case and has a push-button 1^b on it, by which it may be forced 50 inwardly out of contact with the lug 2^a. The

plate 2 has an arm 2^b, which is bent upwardly and over to the center of the base-plate and is forked at the end and straddles a rotary stem 5. This stem has rigidly attached to it a circular plate 3, having two arms 3^a and 3^b 55 projecting radially therefrom. The plate 2 and arm 2^b are always in contact with the circular plate 3 and arms 3^a and 3^b, no matter in what position this plate 3 and its arm may be turned by the stem 5. 60

The stem 5 is seated to turn in a bearing in the base-plate and also in the case and is provided with a button or thumb-piece 5^a, by which it is turned. The arms 3^a and 3^b are designed to make contact with either or both 65 of two springs s^a s^b, connected, respectively, to plates 4 and 4^a.

The current which comes in from main line M' to 1 passes through spring-arm 1^a to plate 2, through arm 2^b to plate 3 and arms 3^a and 3^b, thence to either of the springs s^a or s^b, or to both of them, and to either of the branch lines M² M³, or to both of them, as the case 70 may be. If the two arms 3^a and 3^b are resting on the two springs s^a s^b, the current goes 75 to both lines M² M³. If but one of these arms is on one of the springs, the current goes only to that branch line.

To determine the position of the switch within the case, the upper surface of the case 80 is cut through with perforated or stenciled figures at x, corresponding to the spring-contacts s^a s^b of the branch lines M² M³, and there is attached to the stem 5 a mask-plate 7, having two cut-away portions 7^a 7^b, corresponding 85 in position to the two rotary arms 3^a and 3^b. When these cut-away portions are directly over the stenciled figures in the case, the arms 3^a and 3^b are resting upon the contact-springs s^a and s^b, as the mask-plate and 90 arms 3^a 3^b move together. To make these stencil-figures more distinct, especially in dark places or at night, a small electric lamp L is arranged in the case and has one of its terminals connected to a plate 6 and the other 95 one to a plate 6^a. The plate 6 has an upturned lug 6^b, which is arranged to be struck by the spring 1^a when pressed in, and the other plate, 6^a, is connected to the branch line M⁴. Now when the spring-arm 1^a is forced in by its 100

push-button connection is broken between 1^a and plate 2, cutting out branch lines M² M³, with their light, (shown in Fig. 5,) and connection is made between 1^a and 6 and thence 5 through the electric lamp L, plate 6^a, and branch line M⁴ to the return-wire M⁵. The result is that the lamp L is illumined and the 10 light shining through the stencil-letters in the case shows clearly what connections the switch is adjusted for.

The indicator-light L, it will be seen, is for the purpose of being able to set the switch by pressing in the push-button, which illuminates the indicator-light and throws off all other 15 lights.

As shown, I have provided in my switch for two branch lines M² M³ and two arms 3^a and 3^b and two indicator-figures x; but it is obvious that any number may be employed and 20 any combination or grouping of branch lines may be controlled.

In making use of my switch I may employ it either with or without the indicator-light.

Having thus described my invention, what I 25 claim as new, and desire to secure by Letters Patent, is—

1. A circuit-controlling switch, comprising a base-plate, an inclosing case, a rotary stem bearing a rigidly-attached plate with a plurality of radial contact-arms, an external thumb-piece mounted on the rotary stem, a main-line connection, an arm electrically connected thereto and bent up and over the stem-plate and rubbing thereon, and a plurality of 35 branch-line contacts arranged to be pressed upon by the radial arms of the rotary stem, as shown and described.

2. A circuit-controlling switch, comprising a base-plate, an inclosing case, a rotary stem 40 bearing radial contact-arms, a plurality of contacts with branch-line connections, a main-

line connection, a rubbing-arm in permanent connection with the radial arms, an electric lamp and a movable arm extending through the wall of the case and arranged to alternately break the branch-line circuits and throw in the indicator-lamp substantially as shown and described. 45

3. An electric switch, comprising a rotary movable part having a plurality of circuit-contacts, an inclosing case having stenciled markings through the walls of the same, an electric lamp within the case, a movable arm for throwing the same into circuit and a mask-plate attached to the rotary movable part of 55 the switch and having cut-away portions to expose the stencil-markings in the case whenever the corresponding contacts within the case are in circuit substantially as described. 60

4. An electric switch, comprising a base-plate, an inclosing case with a hole in the side and stenciled markings in the top, a rotary stem mounted in a bearing in the base-plate and extending through the top of the case and provided with a thumb-piece, a rotary 65 plate with radial arms rigidly attached to the stem within the case, corresponding branch-line connections, a main-line connection, an arm connected to the main line and also by a rubbing contact to the radial arms, an electric 70 indicator-lamp in the case, and a spring-arm extending through the side of the case and adapted to break the branch lines and throw in the indicator-lamp, and a mask-plate with cut-out parts attached rigidly to the rotary 75 stem and arranged to expose the stenciled markings in the case which correspond to the contacts within substantially as described.

WARREN K. DODGE.
